BOOKCASE OR SIMILAR ARTICLE

George L. Schaefer, New York, N.Y., and Franklin R. Amthor, Jr., Manitowoc, and James M. Katzfey and Roy E. Kanitz, Two Rivers, Wis., assignors to Hamilton Manufacturing Company, Two Rivers, Wis., a corporation of Wisconsin

Filed Apr. 5, 1963, Ser. No. 74,318

Term of patent 14 years

(Cl. D33—2)

Fig. 3

Fig. 1.

Fig. 5.

FIG. 1 is a front elevational view of a bookcase or similar article embodying our new design;

FIG. 2 is an enlarged sectional view taken on the line 2—2 of FIG. 1;

FIG. 3 is a rear elevational view of the assembly;

FIG. 4 is a right side elevational view of the assembly; and

FIG. 5 is a front perspective view of the construction shown in FIG. 1.

The left side of the assembly not shown is similar in appearance to the side shown.

The dominant features of our design reside in the portions shown in full lines in the drawings.

We claim:

The ornamental design for a bookcase or similar article, substantially as shown and described.
